United States Patent Office

Des. 206,857
Patented Feb. 7, 1967

206,857

TOOTH PASTE TUBE SQUEEZER

Gerald Dalton, 459 North 250th East,
Kaysville, Utah 84037

Filed Mar. 3, 1966, Ser. No. 1,275

Term of patent 14 years

(Cl. D4—3)

FIG. 1 is an enlarged perspective view of the invention;
FIG. 2, a plan view; and
FIG. 3 an end elevation view.

I claim:

The ornamental design for a tooth paste tube squeezer,
substantially as shown.
